UNITED STATES PATENT OFFICE.

ALTER SHUBEN, OF LOS ANGELES, CALIFORNIA, ASSIGNOR TO SHUBENETTE FURNITURE MANUFACTURING CORPORATION, OF LOS ANGELES, CALIFORNIA, A CORPORATION OF CALIFORNIA.

DESIGN FOR A TABLE.

Application filed January 19, 1929. Serial No. 29,678. Term of patent 14 years.

To all whom it may concern:

Be it known that I, ALTER SHUBEN, a citizen of the United States, residing at Los Angeles, in the county of Los Angeles and State of California, have invented a new, original, and ornamental Design for Table, of which the following is a specification, reference being had to the accompanying drawing, forming part thereof.

I claim:

The ornamental design for a table, as shown.

Signed at Los Angeles, in the county of Los Angeles, State of California, this 31st day of December, 1928.

ALTER SHUBEN.
